UNITED STATES PATENT OFFICE.

DANIEL S. MCKENNA, OF SAN FRANCISCO, CALIFORNIA.

ELECTRIC SWITCH AND LOCK-BOX THEREFOR.

1,103,525.

Specification of Letters Patent. Patented July 14, 1914.

Application filed September 8, 1913. Serial No. 788,600.

To all whom it may concern:

Be it known that I, DANIEL S. MCKENNA, a citizen of the United States, residing in the city and county of San Francisco and State of California, have invented new and useful Improvements in Electric Switches and Lock-Boxes Therefor, of which the following is a specification.

This invention relates to electric switches and locks controlling same, and particularly to an electric switch and lock-box for automobiles.

It is one of the objects of the present invention to provide an inexpensive switch and lock-box which may be readily attached to the dash-board of an automobile in such a manner that it may not be surreptitiously detached therefrom.

It is a further object of the invention to provide a switch-box involving a permanent shell and a removable cover with interlocking means; and to provide a switch structure, the movement of which is controlled by a lock key which unlocks the cover. The switch also controls a bolt for locking the box cap to the box proper so that when the switch is thrown in the neutral or inoperative position the operating key may be removed and the box bolt thrown into such relation with the box parts that they may not be separated; the key being removable from the lock cylinder only when the switch arm is in the neutral position.

A further object of the invention is to provide means for breaking the circuit through the switch, when the latter is normally closed, independent of the lock mechanism, as certain conditions of operation of self-propelled vehicles may sometimes require.

The invention consists of the parts and the construction and combination of parts as hereinafter more fully described and claimed, having reference to the accompanying drawings, in which—

Figure 1 is a front elevation of the improved switch and lock-box with the box cover removed. Fig. 2 is a vertical cross section through the structure. Fig. 3 is a front elevation of the switch mechanism in circuit-closing position, with the cover removed. Fig. 4 is a detail plan view of the shell. Fig. 5 is a detail section on line $x-x$ of Fig. 4.

In its illustrated embodiment, my inven-

tion comprises a switch-box or shell 2, which may be of metal and of suitable form and size, the base 3 of which is preferably of non-conducting material, such as fiber, and has perforations 4 at suitable locations 60 for the entrance of lead wires 5 which may run to sources of electrical energy, as batteries and magneto, and to the sparking circuit of the automobile. The box 2 may be attached to the dash-board A of an automobile by bolts or other suitable devices 3', preferably with the nuts inside of the box.

The box 2 is provided with a removable cap or cover 6 externally fitting the box, the cap having a stop shoulder 7 on its interior and adjacent to its bottom edge, which shoulder is registerable with a channel 8 formed for its reception in the surface of the box 2. The latter is also provided with an aperture 9 of sufficient length so that the shoulder 7 will interlock with the walls of the slot 9, bayonet fashion, when the cover 6 is slightly turned on the box 2; there being other bayonet stops 10 on the cover 6 engageable with bayonet slots 11 formed for 80 their reception at suitable intervals in the shell 2.

The center of the cover 6 is provided with an aperture 12 with which the escutcheon plate 13 of a suitable type of lock 14 will 85 register, as a lock of the Yale type, having a cylinder 15, into which may be fitted a key 16 operating in the usual manner upon the detents 17 in the lock 14.

Suitably secured upon and insulated from 90 the inner end of the lock cylinder 15 is a switch plate 18 extending radially in one direction for alternate engagement with the contact terminals 19 and 20 of the circuit wires 5—5, one of which goes to the batteries and the other to the magneto of the electric circuit. When the switch is thrown, by turning the inserted key 16, to one or the other of the terminals 19 or 20, the circuit will be closed through the ground or 100 lead wire 5' which is grounded with the brush through the normally closed switch arm 21 pivotally related to the switch 18. The arm 21 is removable from bearing contact with its respective terminal 22 of the 105 wire 5' by the operation of a suitable device, here shown as consisting of a bell-crank 23, pivoted at 24 upon the panel 3; one end of the bell-crank 23 having an outwardly directed arm 25 passing through a slot 26 in 110

the box 2, so that the operator, when necessary, may rock the lever 25 about the fulcrum 24 and thus open or close the circuit at the end of the arm 21 with relation to the terminal 22. This operation is particularly useful when an automobile is coasting and it is desired to interrupt the circuit momentarily without manipulating the main switch plate 18.

10 It is one of the important objects of the present invention to provide in combination with the switch mechanism and box, means for positively locking the box cover 6 to the box 2 so that the latter can be removed only when the operator of the vehicle is present, by whom the key 16 is inserted and the cylinder 15 turned to a circuit-closing position. This prevents the surreptitious removal of the box cover at any other time 15 and with any other means than by the authorized holder of the key. This key-locking mechanism is shown in the present instance as comprising a bolt 30 slidably mounted upon the box panel 3, the bolt having at its inner end a shoe 31 engageable by a roller 32 which is mounted upon and insulated from the adjacent end 33 of the switch arm 18, or a part movable therewith. The arm 33 swings in an arcuate path, when 20 the switch arm 18 is moved from position to position, and the engagement of the actuating roller 32 with the shoe 31 causes the bolt 30 to be projected positively outwardly and automatically returned by its 25 spring 34 as the roller moves angularly from beneath the bolt 30.

The position of the bolt 30, with relation to the circuit terminals 19 and 20, is such that when the switch 18 is in contact with 30 either of the terminals the bolt is retracted, and when the switch 18 is in the neutral position between the terminals 19—20 and in such a position with relation to the lock 14 that the key can be withdrawn, then the 35 bolt 30 stands projected substantially into the channel 8 of the box 2 and intervenes between the channel and the stud 7 of the cap 6 which has previously been shifted in the slot 9 by the slight turning of the cap 6 upon the box 2. Thus so long as the switch arm 18 is in the intermediate circuit breaking position and the key 16 in the position for withdrawal from the lock 14, then the bolt 30 will stand projected and prevent the 40 turning of the cap 6 so as to carry the stud 7 toward the channel 8, the intermediate portion of which is occupied by the end of the projected bolt 30. Thus when the operator withdraws the key 16 the switch cannot 45 be operated and the cap 6 cannot be removed from the switch-box 2 and the possibility of closing the circuits is effectually obviated.

In operation, the operator desiring to 50 close one of the circuits will insert the key

16 in the lock 14 and turning the key will throw the switch 18 toward one of the other of the terminals 19—20, at which time the circuit-closing arm 21 is normally in contact with its respective terminal 22, thus closing one of the circuits and simultaneously permitting the retraction of the locking bolt 30 so that the box cover 6 may be removed if desired. During the operation of the vehicle should, for any reason, it be desired to temporarily break the circuit, the circuit breaker 21 may be thrown out or disengaged from its spring clip 22 to throw the lever 25 by foot or otherwise; the circuit again being closed by throwing the lever in the opposite direction. This is done independently of the circuit-closing key-lever structure 15—18.

When the operator wishes to cut out the circuit for use he simply turns the key 15 to the neutral position, bringing the switch 18 to the intermediate position between the contacting clips 19—21 and simultaneously and positively projecting the bolt 30 to lock the cover 6 by preventing the turn thereof on the box 2 to bring the stud 7 into the channel 8.

Having thus described my invention, what I claim and desire to secure by Letters Patent is—

1. In an electric switch, a box having a channel, and a lateral aperture communicating therewith, a removable cap having a stop shoulder receivable in the channel and movable into said lateral aperture upon turning of the cap, a spring pressed bolt borne by the box to extend over said aperture to prevent movement of the stop shoulder out of said aperture, a shoe on the bolt, a pivoted switch arm, a roller on the switch arm to engage beneath the shoe to move the bolt to locking position, and key operated means for moving said switch arm to throw said bolt to locking position.

2. In an electric switch, a box having a socket, a removable cap having a part receivable in said socket, a spring pressed bolt borne by the box adapted to engage said part to hold same against movement out of the socket, a shoe on the bolt, a pivoted switch arm engaged with the shoe to move the bolt into and out of locking position, and key operated means to move said switch arm to throw the bolt to locking position.

3. In an electric switch, a box, a removable cap on the box, a slidable bolt for locking said cap on the box, a switch arm, means in connection with said arm to engage the bolt for moving the bolt to locking position during the movement of the switch arm to neutral position, and key operated means to actuate the arm.

4. In an electric switch, a box, a removable cap on the box, means to lock the cap on the cover, a switch arm which actuates

said locking means, key operated means for
operating the switch arm, and means where-
by the key of the key operated means is
withdrawable only when the switch arm is
5 in neutral position, and the locking means
has been moved to locked position by the
switch arm.

In testimony whereof I have hereunto set
my hand in the presence of two subscribing
witnesses.

DANIEL S. McKENNA.
